UNITED STATES PATENT OFFICE

JACOB TELLER AND ARTHUR P. SCHULZ, OF NEW YORK, N. Y., ASSIGNEES TO TELLER CORPORATION, OF CHATTANOOGA, TENNESSEE, A CORPORATION OF TENNESSEE

DESIGN FOR A COMBINED CABINET GAS OR ELECTRIC RANGE AND REFRIGERATOR

Application filed September 10, 1931. Serial No. 41,066. Term of patent 7 years.

To all whom it may concern:

Be it known that we, JACOB TELLER and ARTHUR P. SCHULZ, citizens of the United States and residents of New York city, in the county of New York and State of New York, have invented a new, original, and ornamental Design for a Combined Cabinet Gas or Electric Range and Refrigerator, of which the following is a specification, reference being had to the accompanying drawings, forming a part thereof.

Figure 1 is a front perspective view of our new design of cabinet range and refrigerator; and

Figure 2 is a similar view, with the doors opened, a portion of the figure being broken away for convenience of illustration.

We claim:

The ornamental design for a combined cabinet gas or electric range and refrigerator, as shown.

JACOB TELLER.
ARTHUR P. SCHULZ.
